CLAIM

The ornamental design for a retention member for an earbud, substantially as shown and described.

DESCRIPTION

FIG. 1 is a front, top and right side perspective view of a retention member for an earbud, showing my new design; FIG. 2 is a front view thereof; FIG. 3 is a right side view thereof; FIG. 4 is a rear view thereof; FIG. 5 is a left side view thereof; FIG. 6 is a top view thereof; and, FIG. 7 is a bottom view thereof.

The broken lines illustrate portions of the retention member for an earbud and form no part of the claimed design.
